MECHANICAL VALVE LASH ADJUSTER

Maurice S. Rosenberger, Birmingham, Mich., assignor to General Motors Corporation, Detroit, Mich., a corporation of Delaware

Filed Aug. 20, 1958, Ser. No. 756,177

5 Claims. (Cl. 123—90)

This invention relates to internal combustion engines and the like, and particularly to self adjusting mounts for rockers such as are used in over-head type valve operating mechanisms thereof. More specifically, the invention concerns an improved arrangement for automatically adjusting the rocker fulcrum to take up lash in the system and compensate for thermal expansion and contraction of the parts.

It has heretofore been proposed to effect such adjustment of the so-called "stud mounted valve rocker" of Leach U.S. Patent Re. 24,035 by inter-threading the rocker bearing ball and the supporting stud so that the ball is induced to screw upwardly during each valve lifting stroke, a spring on the stud opposing such ball movement and acting to return the rocker to the "no-lash" condition when the engine valve returns to its seat. It has been found, however, that a very critical friction condition between the bearing surfaces of the ball and rocker exists in that arrangement which limits the durability life below that which is commercially satisfactory. The difficulty arises from the fact that wear of these surfaces caused by rocking movements of the rocker prevents their maintaining the necessary coefficient of friction required for proper rotation of the ball to insure its automatic adjustment axially of the stud. This invention serves to overcome this difficulty by eliminating the effect of bearing-to-rocker friction on the thrust induced rotation required for proper functioning.

The means by which this and other objects of the invention are carried out will be more clearly understood from the following description, having reference to the drawing wherein:

Figure 1 is a fragmentary transverse sectional view through a combustion engine incorporating the improved lash adjuster, certain of the parts being shown in elevation.

Figure 2 is a further enlarged view, similar to Figure 1, showing additional parts of the adjuster in section for greater clarity.

Figure 3 is a plan view of the parts shown in Figure 2.

Figure 4 is a perspective view of the rocker adjusting nut per se.

Referring now in detail to the drawing, there is shown an engine of a conventional over-head valve type including a cylinder block 1 having a cylinder head 2. Slidably guided for axial reciprocation in the bore 3 of the cylinder head is the stem 4 of a poppet valve 5, the upper end 6 of which projects above the cylinder head. Also suitably guided in the cylinder head is a push rod 8 which is disposed laterally of the valve stem 4 and has its upper end 9 also projecting above the cylinder head. The usual valve return spring is shown at 10. The lower end of the push rod abuts a tappet 11 which is slidably guided for axial reciprocation in the tappet bore 12 provided in the cylinder block. A cam 13 is shown on which rests the lower end of the tappet and whose shaft 14 is rotatively driven in any desired

2

manner (not shown) to cyclically lift the tappet and push rod.

Operatively connecting the push rod and valve stem is a valve rocker 15 whose ends 16 and 17 overlie and rest upon the upper ends 9 and 6 of the push rod and valve stem, respectively. Adjacent its end 16 the bottom surface of the rocker is spherically dished to socketably receive the push rod upper end 9 in bearing relation, and intermediate the push rod and valve the rocker is provided on its upper or thrust side with a spherically dished bearing surface 18. Bearing means shown in the form of an annular member 19 has a convex part-spherical bottom surface 20 journaling the rocker surface 19 and thereby establishing the fulcrum axis of the rocker during 15 rocking movements thereof in transmitting oppositely reciprocating movements between the push rod and valve. Centrally of its bearing surface 18 the rocker is provided with an opening 29 through which extends a bearing support in the form of a stud 21, with ample clearance to 20 accommodate full oscillatory movement of the rocker. The cylinder head serves as the support for this stud, as by a press fit of the lower end of the stud therein. The rocker bearing member 19 slidably embraces the stud which serves as a guide therefor and extends therethrough. Axially adjacent the bearing member is a nut 22 having non-locking threads engaging external threads 23 on the stud. The under side of the nut and the upper end of the bearing member 19 have substantially flat annular surfaces 25 and 24, respectively, which coat 30 with each other in thrust and rotary bearing relation. Resilient means, shown in the form of a torsion spring 30 encircling the stud above the nut, has its lower end 26 connected to the nut and its upper end 27 anchored to the stud by a retainer means 28. The retainer means 35 is illustrated in the form of a sheet metal stamping whose central portion 31 is fixed as by a press fit to the upper end of the stud.

The flat annular surface 25 of the nut is limited in width by counterboring the nut as at 32 in order to insure a constant area of contact with the bearing surface 24, which, in turn, serves to maintain a constant coefficient of friction affecting rotation of the nut on the bearing. Such coefficient of friction must be maintained in order that the friction force imposed by the bearing 45 19 in resisting rotation of the nut will not vary substantially with wear of these surfaces. The coefficient of friction between these surfaces must accommodate rotation of the nut under the turning force induced by the non-locking threads in response to the rocker thrust loads 50 imposed by the valve spring 10. This thrust is zero, of course, when the valve 5 is seated and increases proportionately (neglecting inertia effects) with the extent to which the valve is opened by the cam 13. The torsion spring 30 serves both to supplement the friction holding 55 force opposing rotation of the nut by the bearing member during thrust application, and to maintain the nut in abutment with the bearing member as the thrust load is removed.

Accordingly, in operation, during each valve-open 60 period of the cam cycle the thrust load imposed on the rocker is transmitted by its bearing 19 to the nut 22. By reason of the non-locking threads between the stud and nut, the nut is consequently forced to screw upwardly on the stud, against the friction restraining forces imposed by the bearing member at the surfaces 24 and 25 and against the biasing force of the torsion spring 30. When the valve thereafter returns to closed position, thereby relieving the thrust load on the rocker, the torsion spring screws the nut back down on the stud to its initial position, taking up all lash (operating clearance) 65 between the cam 13 and the valve stem 4. Of course, any minute wear of the various abutting surfaces of the valve 70

operating parts as well as thermal expansion and contraction thereof occurring during the cam cycle will be compensated for in establishing a new "initial" position of the nut in the valve-closed condition.

It will be evident that in accordance with the invention as described wear between the bearing member 19 and the rocker, and any consequent change in either the area of their mutually contacting surfaces or coefficient of friction therebetween, is ineffective to alter the controlled extent of threaded adjustment of the nut on the stud during the valve operating cycle, hence proper functioning of the lash adjusting parts is assured.

It is appreciated that various minor changes in the construction and arrangement of the parts will readily suggest themselves to those skilled in the art without departing from the spirit and scope of the invention as hereinafter claimed.

I claim:

1. In a self-adjusting rocker mounting for use in a poppet valve or like operating linkage, a rocker having an opening extending therethrough in the thrust direction, a bearing support extending through said opening, bearing means slidable on said support and journaling the thrust side of the rocker adjacent said opening, a nut on the support oppositely of the bearing means from the rocker, said nut and support being interthreaded with non-locking threads, and resilient means reacting operatively between the support and nut in opposing movement of the nut in the direction of rocker thrust, said nut and bearing means having coacting surfaces accommodating rotation of the nut under rocker thrust loads transmitted thereto by the bearing means.

2. In a support for a rocker having an opening extending therethrough normal to its fulcrum axis, a stud adapted to extend through the opening with clearance accommodating oscillatory movement of the rocker in operation, a nut on the stud, said nut and stud being interthreaded with non-locking threads, a spring secured to the stud and nut and acting to screw the nut therewith in the direction opposite to the direction of rocker thrust, said spring being yieldable to accommodate unscrewing of the nut under thrust loads imposed by the rocker in operation, and a bearing adapted to journal oscillatory movement of the rocker in operation, said nut and bearing having coacting thrust surfaces accommodating nut rotation under the turning force induced by said threads in response to rocker thrust.

3. In combination with a rocker drivingly connected to oppositely reciprocating elements, rocker supporting means including a member journaling the rocker for

50

oscillation about its fulcrum axis, a guide mounting said member for movement in response to rocker thrust, a part rotatably and thrustably bearing on said member and having a non-locking interthreaded connection to the guide whereby rocker operating thrust transmitted to said part by the member induces said part to threadedly rotate on the threads of the guide, and a torsion spring interconnecting the guide and said part and resiliently opposing their relative rotation induced by rocker thrust.

5. In combination with a rocker having an opening extending therethrough in the thrust direction, supporting and journaling means for the rocker including a fixed support, a stud fixed to said support and extending through said opening with sufficient clearance to accommodate rocking movement of the rocker, first and second members embracing the stud oppositely of the rocker from the support and having coacting thrust bearing surfaces, one of said members being slidable longitudinally of the stud and journaling rocking movements of the rocker, the other of said members having a non-locking interthreaded engagement with the stud, and a torsion spring reacting between the stud and said other member to bias the latter in opposition to rotation thereof induced by rocker thrust transmitted by said first member.

5. In combination with a rocker for transmitting motion between oppositely reciprocating driving and driven elements, said rocker having an opening extending therethrough in the thrust direction and a concave bearing surface adjacent the opening on the thrust side of the rocker, a fixed stud extending through the opening with clearance to accommodate rocking movements of the rocker, an apertured bearing slidably embracing the stud having a convex surface journaling said bearing surface of the rocker and a substantially flat annular surface facing away from the rocker, a nut on the stud axially adjacent the bearing and having a substantially flat annular bearing surface rotatably seating on said last named surface of the bearing, said nut and stud having non-locking interengaging threads, a torsion spring encircling the stud on the opposite side of the nut from the bearing, and means anchoring one end of said spring to the extended end of the stud and the opposite end of the spring to the nut, said spring being torsionally stressed to resiliently oppose rotary adjustment of the nut under rocker operating thrust transmitted to the nut by the bearing.
